UNITED STATES PATENT OFFICE.

HARRY L. BRUCE, OF PORTLAND, OREGON.

PROCESS FOR TREATMENT OF FUEL-COKE.

No. 906,379.

Specification of Letters Patent.

Patented Dec. 8, 1908.

Application filed February 18, 1907. Serial No. 358,154.

To all whom it may concern:

Be it known that I, HARRY L. BRUCE, a citizen of the United States, and resident of Portland, in the county of Multnomah and State of Oregon, have invented a new and useful Process for Treatment of Fuel-Coke, of which the following is a specification.

This invention consists in taking "foundry-dry-coke" and filling the pores thereof with crude-oil so that it will readily ignite and continue to burn without requiring a strong draft.

It is well known that foundry-coke possesses high heating value, but it is a difficult substance to keep burning, requiring a strong draft constantly.

To make my improved fuel I take a quantity of the foundry-coke and place the same in a receptacle filled with a mixture of crude-oil and water, and allow the coke to remain in the mixture until it has absorbed all thereof it will hold. I then remove the coke from the mixture and allow it to become surface dry, after which it is in condition to be shipped where wanted. In order to obtain the proper inter-mixture of crude-oil and water sufficient in quantity to saturate about thirty pounds of foundry coke, I take eight pounds of oil and pour the same in sixteen pounds of water, heated to the boiling point, and thoroughly inter-mix the two; the coke is then immersed in said inter-mixture, which is kept in a commingled state by constant agitation during such immersion; the hot water and oil will continue in a suitable inter-mixture to be absorbed in that state by the coke. The oil absorbed by the coke

will impart to the latter the property of becoming more easily ignited, and the oil will also prevent the evaporation of the globules of water contained in the pores of the coke; and after the oil in the pores of the coke has become ignited, the water globules will instantly be converted into a vapor, the gases of which will stimulate the more thorough ignition of the coke. The resultant substance, which I find convenient to call crude-oil coke, is to be used in a furnace about as usual, the fire being readily started with kindlings.

After my crude oil coke has ignited it will continue to burn freely, with a white smokeless flame until both coke and the fluid held in suspension thereby have been completely consumed, and it required only a little draft to keep it going. I find that the crude-oil burns with great heat, and that besides it is very economical, producing a high temperature at less cost than obtained by burning either the coke or crude-oil separately.

I claim:

The process of treating coke, for the purpose mentioned, which consists in immersing the same in a mixture of crude-oil and water, said water being heated to boiling point to facilitate the intermixture therewith of the crude-oil, and the oil and water being kept in a commingled state by constant agitation during said immersion.

HARRY L. BRUCE.
